UNITED STATES PATENT OFFICE.

RICHARD BEAUMONT THOMAS, OF LYDBROOK, COUNTY OF GLOUCESTER, ENGLAND.

CLEANING METAL PLATES OR SHEETS.

SPECIFICATION forming part of Letters Patent No. 398,094, dated February 19, 1889.

Application filed November 22, 1887. Serial No. 255,896. (No model.) Patented in England December 8, 1886, No. 16,065.

To all whom it may concern:

Be it known that I, RICHARD BEAUMONT THOMAS, a subject of the Queen of Great Britain and Ireland, and a resident of Lydbrook, 5 in the county of Gloucester, England, have invented certain Improvements in Cleaning Metal Plates or Sheets, (for which British Patent No. 16,065, dated December 8, 1886, has been obtained,) of which the following is a 10 specification.

The object of my invention is to provide means and appliances for cleaning metal plates or sheets—such, for example, as tin or terne plates—whereby these plates or sheets 15 shall be cleaned with ease and facility. To carry out this object I form carriers for these plates or sheets, which carriers, being mounted on an endless band, cause the plates or sheets to pass through the cleaning material in an 20 upwardly-curved direction as many times as may be necessary with alternate surfaces uppermost.

In the accompanying drawings, Figure 1 is a vertical longitudinal section of my cleaning 25 apparatus. Fig. 2 is a plan of the same. Fig. 3 is a plan of the carrier. Fig. 4 is a plan of the lower part of the carrier. Fig. 5 is a side elevation, and Fig. 6 is a rear elevation, of the carrier.

30 In or on any suitable framing, A, I mount a series of rollers, as is hereinafter described, and round these rollers on each side of the apparatus is the endless band B, preferably formed of and by a suitable chain, that shown 35 in the drawings being very convenient. On these bands B, at suitable intervals, are secured the carriers for the plates or sheets, constructed as follows: Transverse stretchers C are connected to the two bands B at the 40 proper intervals, two such stretchers being required for each carrier, and on the one stretcher C are erected two or more standards, D, which in side view are always at right angles, or thereabout, to the bands B, and at 45 or near the tops of these standards D are horizontally pivoted two or more fingers, E, in such wise that they can be folded or can fall down parallel in plan view with the band B, and can be erected into a position at right 50 angles, or thereabout, in side view, for which purpose these fingers E are counterbalanced

by the plate F, whereto they are all secured, which plate F has a projection, F', on one or both sides, and on the free ends of the fingers E a small plate, E', can conveniently be secured. On this stretcher C also are rigidly secured two or more shorter fingers, G, parallel with the bands B, and on the stretcher C', in front of the same, are similarly secured other like fingers, G', and all these fingers E and 60 G are so proportioned that when the fingers E are folded down on the fingers G the ends of the fingers E or the plate E' thereon about correspond with the ends of the fingers G', on which also may be a similar small plate, 65 if desired. To save the plate from damage, all these fingers and the plates thereon, if any, may be so formed, and, if required, be so covered and with such material as may be expedient or suitable.

The bands B are caused to travel at a somewhat slow speed, and when one of these carriers arrives at the top of the roller H the fingers E will either automatically assume the nearly-vertical position shown in Fig. 1, or 75 can be caused so to do, and a plate is then placed in a nearly-vertical position in this carrier, its lower edge resting on the fingers G, and as the carrier passes on, at a certain desired position, the fingers E, as shown in 80 this Fig. 1, are folded down preferably by a stop engaging the projection F', and the plate then lies flat on the fingers G. When the plate in the carrier has been so laid flat, it passes along above an upwardly-curved platform or open chamber, I, wherein are shudes or other suitable materials, and the two bands B pass under a series of rollers, J, preferably three in number, mounted parallel, or thereabout, with the curved platform I, 90 whereby the plate is caused to enter the cleaning material and to take an upwardly-curved course therein, whereby both surfaces, but more especially the upper surface, of the plate will be most efficiently cleaned, and as 95 the plates in succession are continually passing in this upwardly-curved course there will be little or no danger of the cleaning material falling off or being lifted off the platform I. The bands B then pass round and over 100 the upper roller, J', of this series, whereby the carrier is reversed in position, and the

plate must obviously now rest on the fingers E, which fingers E fall down, as shown in Fig. 1, on another platform or open chamber, K, also upwardly curved, but in an opposite direction, wherein also are shudes or other suitable materials, and the two bands B pass under a series of rollers, L, also preferably three in number, mounted parallel, or thereabout, with the curved platform K, and as the carrier passes on the ends of the fingers E slide on this platform K, whereby the plate, which obviously is now also reversed in position, and what was the lower surface is now the upper surface, is caused to enter the cleaning material and to take an upwardly-curved course therein, whereby both surfaces, but more especially the now upper surface, of the plate will be most efficiently cleaned, and as the plates in succession are continually passing in this upwardly-curved course there will be little or no danger of the cleaning material falling off or being lifted off the platform K. As the carrier approaches the upper end of this platform K, the fingers E gradually open out, as shown in Fig. 1, until the plate slides therefrom into a suitable receptacle or otherwise, or, as is preferable, into the dusting apparatus. The bands B then pass round and over the upper roller, L', of this series, which can conveniently be toothed or otherwise so formed that the motion desired can be given to the bands B by and through this roller L', revolved by any suitable power or gearing or otherwise. From this roller L' the bands B pass round other rollers, M, back to the aforesaid roller H.

It is obvious that the rollers J must be so formed that the standards D of the carriers can pass thereunder, and for the sake of lightness I preferably form all the rollers as shown in the drawings, wherein each roller consists of two disks or wheels mounted loosely on a shaft near the sides of the apparatus, except the roller L', in which the disks or wheels must obviously be rigidly secured to their shaft to give the desired motion to both the bands, and any one or more of the rollers or

the shafts thereof may be so fitted as to be adjustable, thereby giving the bands the required tension.

50

I consider that the two curved platforms or open chambers hereinbefore described are in general amply sufficient to clean the plates; but, when desired, I can fit any number of similar curved platforms or open chambers, 55 causing the plates, in manner as hereinbefore described, to pass over them all in succession with alternate surfaces uppermost.

The plate may be placed in the carrier as it issues from the prior treatment while hot, 60 in which case this apparatus and the bands thereof would be of such a length as will allow the metal to set before the plate enters the cleaning material in the first platform or open chamber.

65

I claim as my invention—

1. The herein-described apparatus for cleaning metal plates or sheets, said apparatus comprising platforms containing cleaning material, a traveling band to carry the plates, and rollers carrying the band, one side up over one platform and the reverse side up over the next platform, as and for the purpose set forth.

70

2. The herein-described apparatus for cleaning metal plates or sheets, said apparatus comprising curved platforms containing cleaning material, a traveling band having rigid and pivoted holding-fingers for the plates, and rollers carrying the band, one side up over one platform and the reverse side up over the next 75 platform, as and for the purpose set forth.

80

3. The herein-described plate-carrying band, comprising endless bands with connecting stretchers, ringers and standards on the stretchers, and counterbalanced fingers pivoted to the standards, substantially as described.

85

In testimony whereof I have signed my name to this specification in the presence of two subscribing witnesses.

RICHARD BEAUMONT THOMAS.
